CIRCUIT INTERRUPTER

Winthrop M. Leeds, Wilkinsburg, Pa., assignor to
Westinghouse Electric Corporation, East Pittsburgh, Pa., a corporation of Pennsylvania

Application January 19, 1945, Serial No. 573,545

12 Claims. (Cl. 200—150)

1

This invention relates to circuit interrupters in general, and, more particularly, to arc extinguishing structures therefor.

In United States Patent 2,253,009 which issued August 19, 1941, to Benjamin P. Baker and which was assigned to the assignee of the instant application, there is shown and described a novel circuit interrupting structure in which a piston member carrying a movable contact causes a separation thereof from a stationary contact disposed at one side of a piston chamber in which the piston member is movable. The resulting arc is drawn longitudinally of the piston member and is subjected to a longitudinal flow of liquid by the piston action of the piston member movable within the piston chamber. The longitudinal flow of liquid effects the extinction of the arc at an early current zero.

It is an object of my invention to adapt an interrupting structure of the foregoing type such that a plurality of inlet passages may be provided to send additional jets of liquid toward the arc. Instead of using one stream of liquid which becomes progressively more contaminated as it flows along the arc, this improved construction brings in clean liquid at a plurality of points and exhausts the arc products at a plurality of intermediate points.

A general object of my invention is to provide a circuit interrupter of improved construction which will more effectively interrupt the circuit therethrough than circuit interrupters involving conventional structure.

Another object is to provide a circuit interrupter generally of the foregoing type in which one or more inlet passages lead toward the arc and through which is forced fluid, preferably liquid, by the piston action of the piston member. Preferably vent passages are disposed adjacent the interrupting arc to permit a ready exhausting of fluid away from said arc.

Further objects and advantages will readily become apparent upon a reading of the following specification taken in conjunction with the drawings; in which:

Figure 1 is an elevational view, partly in section, of a circuit interrupter embodying my invention, the parts being shown in the full open circuit position;

Fig. 2 is a sectional view taken along the line II—II of Fig. 3;

Fig. 3 is a vertical sectional view through a portion of the lower arc extinguishing unit shown in Fig. 1, taken along the line III—III of

2

Fig. 2, the parts being shown in the partly open circuit position;

Figs. 4 through 6 show plate details used in the construction of the arc extinguishing unit shown in Fig. 3;

Fig. 7 shows a modified type of arc extinguishing unit in vertical section, taken along the line VII—VII of Fig. 8, the parts being shown in the partly open circuit position;

10 Fig. 8 is a sectional view taken along the line VIII—VIII of Fig. 7; and

Figs. 9 through 12 show plate details used in the construction of the arc extinguishing unit shown in Fig. 7.

15 Referring to the drawings and more particularly to Fig. 1 thereof, the reference numeral 1 designates a porcelain casing in which is disposed an insulating cylindrical member 2 containing a suitable arc extinguishing fluid 3, in

20 this instance circuit breaker oil, filling the cylindrical member 2 to the level 3a. Disposed within the member 2 is an arc extinguishing assemblage generally designated by the reference numeral 4 and comprising two serially related 25 arc extinguishing units 5. A conducting operating rod 6 is provided to actuate the contact structure within the two units 5. Preferably the upper end of the rod 6 is composed of insulating material as at 7 having the upper end thereof

30 biased downwardly to the open circuit position by accelerating compression springs not shown. A conductor 8 has one end connected to a terminal of the breaker, not shown, and has the other end connected to a terminal 9 of the upper unit 5, 35 the terminal 9 being electrically connected to the stationary contact 23 (see Fig. 3) disposed within the unit 5.

Consequently, the electrical circuit passing through the assemblage 4 comprises line terminal

40 (not shown), conductor 8, terminal 9, stationary contact 23 of the upper unit 5, movable contact 10 movable with the piston member operating within the upper unit 5, to the stationary contact

45 of the lower unit 5 by means, not shown, to the movable contact 10 movable with the piston member 11 associated with the lower unit 5, and through the conducting operating rod 6 through suitable sliding contact means, not shown, to the other line terminal of the breaker. The manner

50 in which the electrical circuit passes through the interrupter is more clearly described in the aforesaid patent, to which reference may be had in obtaining a more clarified picture of the electrical connections.

55 During the opening operation accelerating

compression springs, not shown, cause downward movement of the portion 7 of operating rod 6 to thereby cause downward movement of contact 10 and piston member 11 associated with each unit 5 into the piston chamber 12 associated with each unit 5 to effect thereby a drawing of a single arc longitudinally of the piston member within each unit 5. The displacement of arc extinguishing liquid, in this case oil, by the piston 11 subjects the arc to a multiplicity of liquid jets as described more fully hereinafter. It will be observed that since the two units 5 are connected in a serially related manner, the two arcs drawn within the assemblage 4 are in series to obtain high voltage arc interrupting ability. Extinction of these arcs will effect a breaking of the electrical circuit through the interrupter, and the operating rod 6 will continue to move in a downward direction until the piston member 11 has moved to an extreme position within the piston chamber 12. Disconnect means may be provided to introduce an isolating gap into the circuit after interruption of the arcs drawn within the assemblage 4.

To close the breaker the rod 6 is moved upwardly by suitable means, not shown, to cause an upward movement of both piston members 11 associated with the units 5 to thereby effect a reengagement between the movable contacts 10 secured to the piston members and the stationary contacts 23 disposed at one side of the piston chambers.

Referring more particularly to Figs. 2 and 3 which show more clearly the construction of the lower arc extinguishing unit 5 of Fig. 1, it will be observed that the piston chamber 12 comprises a plurality of suitably shaped plates of insulating material shown more fully in Figs. 4, 5 and 6. The bottom three plates of the unit 5 shown in Fig. 3 are circular in shape and merely have an aperture 13 extending therethrough through which the conducting operating rod 6 extends. These plates may be designated by the reference numeral 14. Immediately above the top plate 14 are two plates 15 having a configuration more clearly shown in Fig. 6 of the drawings. The plate 15 has an enlarged portion 16 removed therefrom. Above the top plate 15 is a plate 17 having a configuration more clearly shown in Fig. 4. The plate 17 has an enlarged portion 18 removed therefrom and also vent portions 19 grooved on the plate 17 to form vent passages, the purpose for which will appear more clearly hereinafter. Above the plate 17 is an inlet insulating plate 19 having a configuration more clearly shown in Fig. 5. The plate 19 has a portion 20 removed therefrom which is of larger diameter than the portion 16 of either plates 15 or 17, the purpose for which will appear more clearly hereinafter. Above the plate 19 is a plate 15, above which is a second plate 17. The plates then repeat in the foregoing manner to the top of the piston chamber 12.

Operative within the piston chamber 12 is a piston member 11 carrying a movable contact 10 and also carrying a plurality of plates 21, alternate plates of which are notched as at 22 to thereby form a plurality of surface irregularities axially along the piston member 11.

The movable contact 10 cooperates with a stationary contact 23 disposed at one side of the piston chamber 12.

During downward or opening movement of the conducting rod 6, the piston member 11 enters the piston chamber 12 to cause a displace-

ment of fluid into a channel 24 formed along a wall of the piston chamber 12. The fluid passes through a plurality of pairs of inlet passages 25 toward the arc 26 drawn between the stationary contact 23 and the movable contact 10. After striking the arc 26, the fluid, in this instance liquid, passes through orifice openings formed between the stationary plates and the moving piston 11, and then exhausts out of the unit 5 through the vent passages 19.

Consequently, during the opening operation the arc 26 is subjected to a flow of oil at a plurality of points along its length. This oil flow is caused by the piston action of the piston member 11 moving into the piston chamber 12. After the oil passes through the inlet passages 25, striking the arc 26 it passes vertically upward and downward through orifice openings and then out vent passages 19 alternately positioned between adjacent inlet passages 25. Extinction of the arc 26 soon follows, and continued downward movement of the piston member 11 causes a flushing flow of oil to pass through the inlet passages 25 and out the vent passages 19.

Certain features of the construction relating to the inlet, orifice, and vent passages are described and claimed in a patent application Serial No. 465,244, filed November 11, 1942, now U. S. Patent 2,406,469, issued August 27, 1946, by Leon R. Ludwig, Winthrop M. Leeds and Benjamin P. Baker and assigned to the assignee of the instant application.

In the modified type of arc extinguishing unit 28 shown in Figs. 7 through 12, it will be observed that the vent passages 29 are formed by removing a portion from the vent insulating plates 30, more clearly shown in Fig. 9. Portions 31 are also removed from the vent plates 30, the purpose for which will appear more clearly hereinafter. The configuration of the inlet insulating plates 32 is more clearly shown in Fig. 10, the inlet passages 25 being formed by the removal of a suitable portion from the plate 32. The bottom insulating plate of the piston chamber 12 is designated by the reference numeral 33 and is more clearly shown in Fig. 12. It will be observed that the portion 31 of plate 33 communicates by a passage 34 to the region 35 within the plate 33, the purpose for which will appear more clearly hereinafter.

Positioned between adjacent vent plates 30 and inlet plates 32 are insulating orifice plates 36 having a configuration more clearly shown in Fig. 11. The orifice plate 36 has portions 31 removed therefrom.

The piston chamber 12 is formed by the assembling of the foregoing plates. It will be observed that an orifice plate 36 is positioned between each vent plate 30 and each inlet plate 32 down to the bottom of the piston chamber 12, at the end of which is positioned the plate 33. As in the unit 5 of Fig. 3, three plates 14 are provided to close the piston chamber 12.

The operation of the modified type of unit 28 will now be described. Upon downward movement of the contact 10 and piston member 11 into the piston chamber 12, an arc 26 is established between the stationary contact 23 and the movable contact 10. The piston action of the piston member 11 forces oil to flow from the region 37 through the passages 34 provided by the plate 33 and into the two vertically extending passages 38 formed by the alignment of the portions 31 of the several plates. The inlet passages 25 have one end thereof communicating with the passages 38

and have their other ends disposed substantially opposite each other to direct jets of oil toward the interrupting arc 26. After the oil has contacted the interrupting arc, it passes out of the unit 28 through the vent passages 29 provided by the vent plates 30. As in the embodiment of my invention described in Fig. 3, surface irregularities are provided on the piston member 11 by notching the plates 21 at 22.

It will be observed that the foregoing interrupting structure with only one pair of contacts in each unit is very compact as compared with the commercial structure embodying the inlet and vent passages as described in the aforesaid Patent 2,406,469 which utilizes both interrupting and pressure generating contacts in each unit.

From the foregoing description, it will be apparent that I have provided contact means for establishing an arc and piston means for actuating the contact means to the open circuit position. Also it will be noted that I have utilized the piston means for forcing fluid through a plurality of inlet passages leading toward the arc and permitting the exhausting away of fluid from the arc through a plurality of vent passages. This results in improved arc interrupting ability as compared with a construction using a single fluid inlet for the whole length of the arc. Also the piston means gives better low current arc rupturing action than is obtained in devices utilizing series-connected pressure-generating arcs.

Although I have shown and described specific structures, it is to be clearly understood that the same were merely for the purpose of illustration, and that changes and modifications may readily be made by those skilled in the art without departing from the spirit and scope of the appended claims.

I claim as my invention:

1. In a circuit interrupter, means forming a piston chamber, a piston member movable within the piston chamber, a movable contact carried by the piston member, a stationary contact disposed at one side of the piston chamber and cooperable with the movable contact to establish an arc, the first-mentioned means having passages formed therein to direct a plurality of pairs of jets of fluid into the arc, each pair consisting of two opposed jets and the pairs being disposed at spaced intervals along the axial length of the arc.

2. In a circuit interrupter, means forming a piston chamber, a piston member movable within the piston chamber, a movable contact carried by the piston member, a stationary contact disposed at one side of the piston chamber and cooperable with the movable contact to establish an arc, said first-mentioned means forming a plurality of pairs of inlet passages leading toward the arc at spaced intervals along the length thereof, each pair permitting two opposed jets of fluid to strike the arc, and said means also forming a plurality of vent passages at intermediate levels leading away from the arc.

3. In a circuit interrupter, means forming a piston chamber, a piston member movable within the piston chamber, a movable contact carried by the piston member, a stationary contact disposed at one side of the piston chamber and cooperable with the movable contact to establish an arc, the first-mentioned means having passages formed therein to direct a plurality of pairs of jets of fluid into the arc, each pair consisting of two opposed jets and the pairs being disposed at spaced intervals along the axial length of the

arc, the first-mentioned means also forming a plurality of venting passages disposed at intermediate levels along the axial length of the arc, and said means in addition providing orifice openings between adjacently positioned inlet and vent passages.

4. In a circuit interrupter, plate means of insulating material forming a piston chamber, a piston member movable within the piston chamber, a movable contact carried by the piston member, a stationary contact disposed at one side of the piston chamber and cooperable with the movable contact to establish an arc, certain plates forming a plurality of pairs of inlet passages leading toward the arc at spaced intervals along the length thereof, each pair permitting two opposed jets of fluid to strike the arc, and other plates forming a plurality of vent passages leading away from the arc at intermediate intervals, the piston action of the piston member movable within the piston chamber forcing fluid through the inlet passages toward the arc.

5. In a circuit interrupter, contact means for establishing an arc, piston means for actuating the contact means to the open circuit position, means forming a plurality of pairs of inlet passages leading toward the arc at spaced intervals along the length thereof, each pair permitting two opposed jets of fluid to strike the arc, and the piston means forcing fluid through the plurality of inlet passages toward the arc.

6. In a circuit interrupter, contact means for establishing an arc, piston means for actuating the contact means to the open circuit position, plate means of insulating material forming a plurality of pairs of inlet passages leading toward the arc at spaced intervals along the length thereof, each pair permitting two opposed jets of fluid to strike the arc, the piston means forcing fluid through the plurality of inlet passages toward the arc, and plate means of insulating material forming a plurality of vent passages leading away from the arc at intermediate intervals.

7. In a circuit interrupter of the liquid break type, means forming a piston chamber, a stationary contact disposed adjacent one side of the piston chamber, a piston member carrying a movable contact movable within the piston chamber, the separation of the movable contact from the stationary contact establishing an arc longitudinally of the piston member between the latter and the piston chamber, the piston chamber having two passages formed in the walls thereof communicating at one end with the bottom of the piston chamber, and the piston chamber having a plurality of pairs of inlet passages formed therein at spaced intervals therealong communicating with the aforesaid two passages at one end and opposing one another at the other end to direct jets of fluid toward each other into the arc to effect the extinction thereof.

8. In a circuit interrupter of the liquid break type, means forming a piston chamber, a stationary contact disposed adjacent one side of the piston chamber, a piston member carrying a movable contact movable within the piston chamber, the separation of the movable contact from the stationary contact establishing an arc longitudinally of the piston member between the latter and the piston chamber, the piston chamber having a recess extending axially thereof and forming a pressure chamber, and the piston chamber having a plurality of pairs of inlet passages formed therein at spaced intervals therealong communicating at one end with the pres-

sure chamber, each pair of inlet passages opposing each other at their other ends to direct jets of fluid toward each other into the arc to effect the extinction thereof.

9. In a circuit interrupter of the liquid break type, means forming a piston chamber, a stationary contact disposed adjacent one side of the piston chamber, a piston member carrying a movable contact movable within the piston chamber, the separation of the movable contact from the stationary contact establishing an arc longitudinally of the piston member between the latter and the piston chamber, the piston chamber having two passages formed in the walls thereof communicating at one end with the bottom of the piston chamber, the piston chamber having a plurality of pairs of inlet passages formed therein at spaced intervals therealong communicating with the aforesaid two passages at one end and opposing one another at the other end to direct jets of fluid toward each other into the arc to effect the extinction thereof, and a plurality of vent passages formed in the walls of the piston chamber alternately disposed between the pairs of inlet passages.

10. In a circuit interrupter of the liquid break type, means forming a piston chamber, a stationary contact disposed adjacent one side of the piston chamber, a piston member carrying a movable contact movable within the piston chamber, the separation of the movable contact from the stationary contact establishing an arc longitudinally of the piston member between the latter and the piston chamber, the piston chamber having a recess extending axially thereof and forming a pressure chamber, the piston chamber having a plurality of pairs of inlet passages formed therein at spaced intervals therealong communicating at one end with the pressure chamber, each pair of inlet passages opposing each other at their other ends to direct jets of fluid toward each other into the arc to effect the extinction thereof, and a plurality of pairs of vent passages formed in the walls of the piston chamber, each pair of vent passages being disposed between adjacent pairs of inlet passages.

11. In a circuit interrupter of the liquid break type, means forming a piston chamber, a stationary contact disposed adjacent one side of the

5 piston chamber, a piston member carrying a movable contact movable within the piston chamber, the separation of the movable contact from the stationary contact establishing an arc longitudinally of the piston member between the latter and the piston chamber, the piston chamber having two passages formed in the walls thereof communicating at one end with the bottom of the piston chamber, the piston chamber having a plurality of pairs of inlet passages formed therein at spaced intervals therealong communicating with the aforesaid two passages at one end and opposing one another at the other end to direct jets of fluid toward each other into the arc to effect the extinction thereof, and the piston member having a plurality of surface irregularities formed thereon.

piston chamber, a piston member carrying a movable contact movable within the piston chamber, the separation of the movable contact from the stationary contact establishing an arc longitudinally of the piston member between the latter and the piston chamber, the piston chamber having two passages formed in the walls thereof communicating at one end with the bottom of the piston chamber, the piston chamber having a plurality of pairs of inlet passages formed therein at spaced intervals therealong communicating with the aforesaid two passages at one end and opposing one another at the other end to direct jets of fluid toward each other into the arc to effect the extinction thereof, and the piston member having a plurality of surface irregularities formed thereon.

12. In a circuit interrupter of the liquid break type, means forming a piston chamber, a stationary contact disposed adjacent one side of the piston chamber, a piston member carrying a movable contact movable within the piston chamber, the separation of the movable contact from the stationary contact establishing an arc longitudinally of the piston member between the latter and the piston chamber, the piston chamber having a recess extending axially thereof and forming a pressure chamber, the piston chamber having a plurality of pairs of inlet passages formed therein at spaced intervals along the length thereof communicating at one end with the pressure chamber, each pair of inlet passages opposing each other at their other ends to direct jets of fluid toward each other into the arc to effect the extinction thereof, and the piston member having a plurality of surface irregularities formed thereon.
